US00D951269S

(12) **United States Design Patent** (10) Patent No.: **US D951,269 S**
(45) Date of Patent: **** May 10, 2022**

(54) **DISPLAY SCREEN OR PORTION THEREOF
WITH GRAPHICAL USER INTERFACE**

- (71) Applicant: **Apple Inc.**, Cupertino, CA (US)
(72) Inventors: **Laurent Baumann**, Campbell, CA (US); **Richard Dellinger**, San Jose, CA (US); **Angela Guzman Suarez**, San Mateo, CA (US); **Raymond Sepulveda**, San Jose, CA (US)
(73) Assignee: **Apple Inc.**, Cupertino, CA (US)
(**) Term: **15 Years**
(21) Appl. No.: **29/726,275**
(22) Filed: **Mar. 2, 2020**

Related U.S. Application Data

(63) Continuation of application No. 29/687,833, filed on Apr. 16, 2019, now Pat. No. Des. 877,180, which is a continuation of application No. 29/507,081, filed on Oct. 23, 2014, now abandoned, which is a continuation of application No. 29/432,574, filed on Sep. 17, 2012, now Pat. No. Des. 716,343, which is a continuation of application No. 29/412,664, filed on Feb. 7, 2012, now abandoned.

CLAIM

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
